UNITED STATES PATENT OFFICE

2,166,964

ELECTRIC FURNACE ROOF RING

William E. Moore, Pittsburgh, Pa., assignor to
Pittsburgh Research Corporation, Pittsburgh,
Pa.

Application June 7, 1937, Serial No. 146,917

2 Claims. (Cl. 122—6)

The present invention relates to improvements in electric furnaces, and more particularly to the roof arch supporting rings therefor.

Heretofore in the operation of electric furnaces, such for example as those used in metallurgical operations, considerable difficulty has been experienced due to the burning away of the shell refractories adjacent the roof ring, causing the refractories next to the supporting flange 10 of the ring to spall or wear away, exposing the roof ring. The consequent overheating of the roof ring soon causes oxidation, crumbling and cracking, and also causes upsetting of the roof ring flange due to expansion.

15 An important object of the present invention is to overcome these difficulties by preventing overheating of the roof ring and adjacent refractories, and by preventing upsetting of the ring flange due to expansion.

20 Other objects and advantages of the invention will be apparent during the course of the following description.

In the accompanying drawing, which forms a part of this specification, and wherein like characters of reference denote like parts throughout,

25 Figure 1 is a vertical sectional view through the roof of an electric furnace embodying the invention, and the adjacent portions of the furnace crucible.

Figure 2 is a horizontal sectional view on the line 2—2 of Figure 1.

Figure 3 is a detail fragmentary vertical sectional view of the improved roof ring, and,

30 Figure 4 is a fragmentary detail sectional view taken on a horizontal plane through the roof ring.

In the drawing, wherein for the purpose of illustration is shown a preferred embodiment of the invention, the numeral 10 designates the metal shell of a furnace crucible having the usual refractory lining 11. A metallic roof ring 12 having an upper inwardly projecting flange 13 and a lower inwardly projecting flange 14 supports the usual roof refractories 15 formed in an arch.

35 In practice the roof ring rests upon the top of the crucible, and is normally protected from the heat of the furnace by the refractories 15. Due to the intense heat to which they are subjected, the refractories often burn away, thereby exposing the metal of the roof ring to the heat of the furnace. This heating of the roof ring results in oxidation of the metal thereof and an upsetting action of the lower flange of the ring. When

the roof ring cools, the strains due to contraction are very severe because of the upsetting of the ring flange, and cracking consequently results.

To overcome this difficulty, a water cooling pipe or channel 16 is arranged in the angle between the roof ring and its lower flange and extends substantially completely around the roof ring, having its ends extended out through the side of the ring for connection to suitable water circulating conduits. In order to insure a direct transfer of heat from the lower flange of the roof ring to the cooling pipe 16, the pipe is welded to the ring and its flange, as indicated at 17. The roof refractories 15 surround the cooling pipe 16.

Despite the presence of the cooling pipe 16, the inner edge of the lower roof flange 14 is often subject to overheating and consequent expanding, which results in upsetting of the inner edge 20 of the flange. When the flange cools down, the contraction of the outer edge thereof is very severe, due to the upsetting caused by the expansion of the edge of the flange while the outer portion of the flange is much cooler and not 25 subject to expansion. The contraction of the upset portion of the flange causes cracking thereof.

To overcome this difficulty, radial slots 18 are cut in the flange and extend from the inner 30 edge of the flange to a point adjacent the welding 17 of the pipe 16 to the ring. The slots 18 are disposed at regular intervals of a few inches about the flange 14, and when these slots are present, no upsetting of the flange occurs when it 35 is overheated, and no cracking occurs when it cools. The slots 18 provide for expansion of the metal of the flange.

It will be seen that the water cooling pipe 16 and its connection to the roof ring prevent overheating of the ring, and that the radial slots 18 permit expansion and contraction of the inner edge of the lower flange 14 without cracking or damaging the flange. When a roof ring is formed with the cooling pipe 16 and slots 18 it 45 will not be subject to the usual damage and deterioration from overheating and the resulting expansion and contraction.

While I have shown and described the preferred embodiment of the invention it is to be 50 understood that various changes in the size, shape and arrangement of parts may be resorted to without departing from the spirit of the invention or the scope of the subjoined claims.

Having thus described my invention, what I 55

claim and desire to protect by Letters Patent is:

1. In a furnace, a furnace crucible, a roof structure for said crucible, said roof structure comprising a metallic roof ring adapted to be supported on said crucible and having an inwardly extending flange at its lower end, said flange being provided with a series of spaced slots extending to the inner edge of the flange, a cooling pipe extending around the interior of said roof ring adjacent the flange, and a refractory roof supported by said roof ring and flange.
2. In a furnace, a furnace crucible, a roof structure comprising a metallic roof ring adapt-

ed to be supported on said crucible and having an inwardly extending flange at its lower end, said flange being provided with a series of spaced slots extending radially inwardly from the inner edge of the flange to permit expansion and contraction of the flange, a cooling pipe extending about the interior of the roof ring and being welded to the flange adjacent the outer edge thereof to insure a high rate of heat transfer from the flange to the cooling pipe, and a refractory roof supported by the roof ring and flange. 5 10
